US00D959372S

(12) **United States Design Patent** (10) **Patent No.:** **US D959,372 S**
Li (45) **Date of Patent:** **** Aug. 2, 2022**

(54) **POWER PLUG**

(71) Applicant: **LINHAI QIGUANG LIGHTING CO., LTD.**, Taizhou (CN)

(72) Inventor: **Yue Li**, Linhai (CN)

(73) Assignee: **LINHAI QIGUANG LIGHTING CO., LTD.**, Taizhou (CN)

(**) Term: **15 Years**

(21) Appl. No.: **29/816,894**

(22) Filed: **Nov. 25, 2021**

(51) LOC (13) Cl. **13-02**

(52) U.S. Cl.

USPC **D13/110**

(58) **Field of Classification Search**

USPC D13/107, 108, 110, 137.1, 137.2, 137.3, D13/137.4, 138.1, 138.2, 139.1, 139.2, D13/139.3, 139.4, 139.5, 139.6, 139.7, D13/139.8, 146, 151, 152, 153, 154, 158, D13/159, 160, 161, 162, 162.1, 163, 164, D13/165, 166, 167, 168, 169, 171, 172, D13/173, 174, 175, 176, 177, 178, 179, D13/184, 199

Assistant Examiner — Seth David Kumpf

(57) **CLAIM**

The ornamental design for a power plug, as shown and described.

DESCRIPTION

FIG. 1 is a perspective view of a power plug showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the power plug that form no part of the claimed design.

1 Claim, 8 Drawing Sheets
